UNITED STATES PATENT OFFICE.

THOMAS VILLAGE, OF CROMWELL, CONNECTICUT, ASSIGNOR TO STEVENS & BROWN MANUFACTURING COMPANY, OF SAME PLACE.

DESIGN FOR MATCH-BOX.

Specification forming part of Design No. **6,147**, dated September 17, 1872.

To all whom it may concern:

Be it known that I, THOMAS VILLAGE, of Cromwell, in the county of Middlesex and State of Connecticut, have invented a Design for Match-Boxes, of which the following is a specification:

The nature of my design is fully represented in the accompanying photographic illustration, to which reference is made.

A is a plate of ornamental contour, forming the back of the box, and is provided with holes *aa* for its attachment by nails to any support. B is a metal shell, formed to represent the bust of the Honorable Horace Greeley with a slouched hat on his head. This is attached to

the plate A, and constitutes the front, sides, and bottom or body of the box. Over the head there is formed on the plate A, in bass-relief, a spade and pitchfork with crossed handles, and a sickle encircling the crossed portions. On each side of the head is a bass-relief representing a sheaf of wheat.

What I claim as my invention is—

The design for match-boxes, substantially such as above described.

THOMAS VILLAGE.
